(57) **CLAIM**

The ornamental design for a protective case, as shown and described.

DESCRIPTION

FIG. 1 is a front perspective view of a protective case according to a first embodiment of our design;

FIG. 2 is a front elevation view of the protective case of FIG. 1 to which a rear elevation view is a mirror image thereof; FIG. 3 is a right elevation view of the protective case of FIG. 1;

FIG. 4 is a left elevation view of the protective case of FIG. 1; FIG. 5 is a top elevation view of the protective case of FIG. 1; FIG. 6 is a bottom elevation view of the protective case of FIG. 1;

FIG. 7 is a front perspective view of the protective case according to a second embodiment of our design shown in an open configuration thereof;

FIG. 8 is a front elevation view of the protective case of FIG. 7 to which a rear elevation view is a mirror image thereof; FIG. 9 is a right side elevation view of the protective case of FIG. 7;

FIG. 10 is a left side elevation view of the protective case of FIG. 7; FIG. 11 is a top elevation view of the protective case of FIG. 7;

FIG. 12 is a bottom elevation view of the protective case of FIG. 7;

FIG. 13 is a front perspective view of a protective case according to the second embodiment of our design shown in a closed configuration thereof;

FIG. 14 is a front elevation view of the protective case of FIG. 13 to which a rear elevation view is a mirror image thereof; FIG. 15 is a right elevation view of the protective case of FIG. 13;

FIG. 16 is a left elevation view of the protective case of FIG. 14;

FIG. 17 is a top elevation view of the protective case of FIG. 13;

FIG. 18 is a bottom elevation view of the protective case of FIG. 13;

FIG. 19 is a front perspective view of the protective case according to the second embodiment of our design shown in a collapsed configuration thereof;

FIG. 20 is a front elevation view of the protective case of FIG. 19 to which a rear elevation view is identical;

FIG. 21 is a right side elevation view of the protective case of FIG. 19;

FIG. 22 is a left side elevation view of the protective case of FIG. 19;

FIG. 23 is a top elevation view of the protective case of FIG. 19; and,

FIG. 24 is a bottom elevation view of the protective case of FIG. 19.

Broken lines are environmental only and form no part of the claimed design.

Dash-dot lines adjacent un-shaded areas represent bounds of the claimed design and form no part of the claimed design themselves.
